Inventor
By her Attorney,
J. R. Littell

UNITED STATES PATENT OFFICE.

MARY AGNES DUNN, OF NEW YORK, N. Y.

BOTTLE, STOPPER, AND OPENER.

SPECIFICATION forming part of Letters Patent No. 752,049, dated February 16, 1904.

Application filed January 26, 1903. Serial No. 140,518. (No model.)

To all whom it may concern:

Be it known that I, MARY AGNES DUNN, a citizen of the United States, residing at New York, in the county and State of New York, have invented certain new and useful Improvements in Bottles, Stoppers, and Openers, of which the following is a specification.

My invention relates to bottles and to means for both stopping and opening them, and is capable of being embodied in such a form that it may be used for either purpose and at the same time be simple and inexpensive.

My invention has for a specific object a mutilation of the bottle, which result will be coincident with opening said bottle, the latter being thereby rendered unfit for refilling for commercial purposes.

In the drawings, Figure 1 is a side elevation of a bottle and a device embodying my invention. Fig. 2 is a bottom plan view of the latter, and Fig. 3 is a vertical longitudinal section of a detail.

Corresponding parts in all the figures are denoted by the same reference characters.

Referring to the drawings, 1 designates a bottle having a body 1' and a neck 2, into which a cork 3 may be inserted. The neck 2 is circumferentially recessed, as at 2', sufficiently to materially reduce the thickness of the wall 30 of the neck, and thus form a shoulder 2''. A wire band 4, which may have an angular edge 4' formed on its perimeter, closely encircles the neck at the recess 2' and is continuedly formed into finger-loops 4'', the edge 4' being inward in the recess 2', but preferably outward on the finger-loops 4''. A strap 5, preferably of wire, is looped at each of its ends 5' to the wire 4 at opposite sides of the recess 2' and passes longitudinally of and over the 40 end of the neck 2 and across the outer end of the cork 3.

The operation and advantages of my invention will be readily understood by those skilled in the art to which it appertains. The device 45 being properly attached to a corked bottle, as above set forth, the cork 3 is held firmly in the neck 2 by the wire strap 5, attached to the wire 4, as aforesaid. When it is desired to open the bottle 1, fingers of one hand may 50 be inserted in the loops 4'', the bottle being

held in the other hand. A sharp pull on the device will then sever the neck at the recess 2, and a lower portion 3' of the cork 3 will prevent broken glass from entering the body 1' of the bottle. It will be noted that a bottle thus opened will be so mutilated, as aforesaid, as to be unfit for further commercial use, and that a bottle so mutilated could not be readily sold with counterfeit contents.

I do not desire to be understood as limiting myself to the details of construction and arrangement as herein described and illustrated, as it is manifest that variations and modifications may be made in the features of construction and arrangement in the adaptation 65 of the device to various conditions of use without departing from the spirit and scope of my invention and improvements. I therefore reserve the right to all such variation and modification as properly fall within the 70 scope of my invention and the terms of the following claims.

Having thus described my invention, I claim and desire to secure by Letters Patent—

1. The combination with a bottle whose neck 75 is provided with a peripheral recess, and a stopper within said neck, of a band encircling said neck within said recess and having an angular edge formed on its perimeter adjacent to the bottle-neck and also having finger-loops, 80 and a fastener securing the stopper in the bottle-neck.

2. The combination with a bottle whose neck is provided with a peripheral recess, and a stopper within said neck, of a band encircling 85 said neck within said recess and provided with finger-loops, said band and finger-loops being composed of wire having an angular edge on its perimeter, and the said edge being inward on the band and outward on the finger-loops, 90 whereby it will sever the neck at the recess and will preclude injury to a person's fingers inserted in the finger-loops, and means for securing the stopper in the bottle-neck.

In testimony whereof I have signed my name 95 in the presence of the subscribing witnesses.

MARY AGNES DUNN.
